UNITED STATES PATENT OFFICE.

JEAN CAVALLIER, OF NANCY, FRANCE, ASSIGNOR TO SOCIETE ANONYME DES HAUTS-FOURNEAUX ET FONDERIES DE PONT-A-MOUSSON, OF PONT-A-MOUSSON, MEURTHE-ET-MOSELLE, FRANCE, A FRENCH COMPANY.

COMPRESSOR.

Application filed January 14, 1927, Serial No. 161,210, and in France January 20, 1926.

The present invention has for its subject an air compressor with blades essentially characterized by the application of a device for guiding the blades on ball bearings, said

5 device eliminating friction of the blades and consequently enabling a good mechanical efficiency to be obtained.

In a general manner the compressor forming the subject of the invention is formed by 10 a cylindrical body made slightly oval, in the interior of which is located a drum carrying blades, the axis of the drum being displaced in relation to that of the body of the compressor. The blades are disposed in 15 grooves provided in the drum extending along diametral planes and they are guided, at the central part thereof, by means of a trunnion held at its two ends and on which they are mounted through the medium of 20 ball bearings.

For the operation of the device a continuous rotary movement is imparted to the drum and this rotary movement produces a to and fro movement of the blades in the interior of 25 their bearings in the drum.

In the accompanying drawings, there are 30 illustrated diagrammatically and solely by way of example two forms of construction of the compressor forming the subject of the invention.

Figure 1 is a longitudinal section, along the axis, of a compressor constructed in accordance with the first form of construction of the invention.

35 Figure 2 is a section on the line II—II of Figure 1.

Figure 3 is a front view of one of the blades.

40 Figure 4 is a section on the line IV—IV of Figure 3.

Figure 5 is a front view of the blade adapted to be connected with that in Figures 3 and 4.

45 Figure 6 shows separately the trunnion on which the blades are mounted.

Figure 7 shows a longitudinal section, along the axis, of a simplified modification of the same apparatus.

50 In the forms of construction illustrated and described the compressor is provided with two double blades disposed in planes at right angles but it will be understood that the invention is not limited to this particu-

lar case and that, according to the applications of the invention, the compressor may 55 be provided with a number of blades other than two.

As shown in Figures 1 and 2 the apparatus is provided with a compressor body 1 of general cylindrical shape but made slightly oval 60 in cross section, closed at its two ends by bases 2 and 3. The body 1 and the bases may, if desired, be provided on their outer surface with fins 4 adapted to increase the radiation surface and thus facilitate the 65 cooling of the compressor. These fins may however be omitted in a number of cases.

In the interior of the body of the compressor 1 is mounted a drum 5 of which the shaft 14, as shown in Figure 2, is displaced 70 relatively to the body of the compressor 1.

In the drum 5 are provided grooves disposed along diametral planes and two in number in the example described. In each of the grooves thus formed is adapted to 75 move a blade. These blades 6 and 7, which are preferably constructed of light metal, (an alloy of aluminium for example), are made of a particular shape as shown in Figures 3 to 5 in order to enable them, in combination with the device to be hereinafter described, to carry out a to and fro movement in the grooves of the drum. As shown in Figure 4 each blade forms, at the middle or central part thereof and at each end, a 80 kind of frame 6' which is preferably lined on the interior on two opposite faces with plates 8 of hard metal by means of which the blade rests on the ball bearings 13 hereinafter referred to.

The object of the frames 6' of the blade is to ensure guiding during rotation, this guiding being obtained by means of a trunnion 9 held at its two ends in such a manner as to prevent it from being out of perpendicular. For this purpose the trunnion 9 is keyed at 10 in the base or plate 3 and at the other end is held in a ball bearing 11 in the interior of the drum 5. Figure 6 shows the construction of the trunnion 9 after removal of the member 12 which simply serves to render it rigid and to prevent vibrations during operation.

The blades 6 and 7 are mounted on the trunnion 9 through the medium of ball bearings 13.

This arrangement eliminates friction of the blades on the inner surface of the body of the compressor 1.

It may be mentioned that by reason of the particular shape which is being given to the blades 6 and 7 the latter are held at their two ends which prevents these members from moving out of perpendicular. This is one of the characteristic features of the device 10 forming the subject of the invention.

The method of operation of the apparatus is the following.

The shaft 14 has a rotary movement imparted thereto by any suitable mechanism 15 and the eccentrically mounted drum 5 partakes of this movement in the interior of the body 1 of the compressor. This movement of the drum produces a to and fro movement of the blades in their guide 20 grooves and the volume produced is that which the blades draw in during their movement of rotation. The fluid to be compressed enters the apparatus through the tubular member 15 (Figure 2) and, after being compressed 25 is discharged through the tubular member 16. The drum is carried by two ball bearings disposed the one, the bearing 17, between the hub 18 of the drum and the base 2 of the compressor, the other, the bearings 19, between the plate 20 of the drum and the base 3 of the compressor. In this manner the drum is prevented from moving 30 out of the perpendicular and the rotation of this member is effected under the best conditions.

The fluid tightness of the bearing of the driving shaft 14 is effected without any gland by a chamber of "metalline" 21 of which the tightening is effected by means of 40 the screw 22.

In the method of construction shown in Figure 1, the lubrication of the compressor is effected by means of an independent oil box mounted in a movable manner on the 45 end of the compressor opposed to that which permits of the passage of the driving shaft. The lubricating device is constructed in the following manner: a bell 23, forming an oil box, is secured, as stated, on the base 3. It is provided at its upper portion with a plug 50 24 for filling and at its lower portion with a pointed screw 25 for the adjustment of the outflow. The bottom 3 of the compressor is pierced at its upper end with a small orifice 55 26 which may be extended, to the interior of the oil box, by a passage 27. The pressure existing in the interior of the compressor, during the operation of this apparatus, acts upon the surface of the oil contained in the box 23 and consequently causes the flow of 60 this oil which penetrates the trunnion 9 (suitably provided with passages), through the orifice 28.

By reason of the provision of this device 65 lubrication only takes place during the oper-

ation of the compressor. The oil is supplied drop by drop and the lubrication is thus effected under the best conditions.

The lubricating device which has been described may be omitted when the apparatus 70 is combined with a machine having a system of lubrication under pressure. This is particularly the case when the compressor is connected with internal combustion engines provided with lubrication under pressure. 75 In this case the orifice 28, communicating with the trunnion 9 is connected in any suitable manner to the oil passages under pressure of the engine.

Figure 7 shows a simplified modification 80 of the compressor which will be described, this modification being particularly suitable for the feeding of internal combustion engines. The general arrangement of this apparatus is similar to that which has been 85 described with the first form of construction, but the trunnion of particular shape as shown in Figure 6 is in this case replaced by a straight line trunnion 9 mounted solidly in the bases 2' and 3' of the compressor. 90 The drum 5' is also extended into the interior of the base 2' which is recessed for this purpose, by means of a pinion 29 by means of which there is effected the production of the rotary movement of the drum. This pinion 95 29 may either engage with another pinion suitably mounted, or receive a chain passing through an opening provided for this purpose in the base 2'.

The rotation of the drum 5' produces the 100 results above set forth.

The compressor which has been described may be used for all the usual applications of apparatus of this type; it is suitable in any case more particularly for the feeding 105 of internal combustion engines and particularly of automobile engines. For these applications the small volumes under which it can be constructed forms a very important 110 advantage. The application of this apparatus may be effected as a compressor for distribution at low and at high pressure.

Having thus described my invention what I claim as new and desire to secure by Letters Patent is:—

1. A blade compressor comprising a casing forming a compression chamber of slightly oval cross section, a drum rotatably mounted within said casing upon an axis parallel to, but offset with respect to the axis of said compression chamber, blade units each comprising a pair of blades rigidly associated, and oppositely disposed, arranged in said drum with the blades projecting through slots in said drum, the blades of the respective units being disposed in perpendicular planes, means permitting each unit to move diametrically in the plane of its blades, and means for holding the blade units at their two ends to prevent them being moved out 130

of perpendicular relation, comprising frames at the ends of the units each having a bearing opening elongated in the diametrical direction of movement of the blades of the unit 5 of which it forms a part, a trunnion eccentrically mounted with respect to the axis of said drum, and bearings surrounding said trunnion and slidable in said bearing openings.

10 2. A compressor according to claim 1, the trunnion being mounted immovably within said drum, whereby reciprocation of said

blades is produced upon rotation of said drum.

3. A compressor according to claim 1, said 15 blades of a pair having connecting portions surrounding said trunnion and limited in movement by contacting therewith at the outward extremities of their reciprocation, thus relieving the inner surface of the compressor 20 body from friction of the blades on the inner surface of the compressor body.

JEAN CAVALLIER.
